GEORGE W. CARPENTER, OF JARVIS, INDIANA.

Letters Patent No. 75,857, dated March 24, 1868.

IMPROVEMENT IN COMBINED WEATHER-STRIP AND DOOR-ALARM.

The Schedule referred to in these Letters Patent and making part of the same.

TO ALL WHOM IT MAY CONCERN:

Be it known that I, GEORGE W. CARPENTER, of Jarvis, De Kalb county, State of Indiana, have invented certain new and useful Improvements in "Combined Weather-Strip and Alarm for Doors," and do hereby declare that the following is a full, clear, and exact description thereof, reference being had to the accompanying drawings, and to the letters of reference marked thereon, making a part of this specification.

In the annexed drawings, A represents the door, which is of any ordinary description, and attached to the frame B. Connected to the lower edge of the door is a metal plate, C, which is made to project beneath the lower edge of the door, in the usual manner. The sill is rabbeted and provided with a strip of metal, g, running its entire length, so when the door is closed the plate C falls of its own weight, and lies outside of the strip g to prevent the ingress of water, dirt, &c. The outer lower edge of the door is slightly cut, wherein is pivoted an eccentric-plate, D, which is shielded by a plate, a, on the edge of the door. The plate D has a cam formed on its forward end, and extends to the front as well as to the rear of the door. Connected to the rear of this plate D is a rod, E, which extends up the inside of the door, and is attached to the end of a metal plate, F, pivoted (in its centre) to the door. G represents a cam pivoted to the door near the plate F, and which said cam has two lugs on its inner face, at opposite sides, and is provided with a clapper, J, connected to it by means of an extending-rod. This clapper is so placed as to lie directly beneath a bell, H, of any suitable construction, placed on the door. K represents a small spring, which is secured to the door, and having one end lie against one of the lugs x on the cam G.

It will be seen that my invention is intended for the double purpose of preventing the water, cold, dirt, &c., from entering the house, and at the same time to alarm the inmates when any one enters. When the door is closed, the edge of the frame keeps the outer point of the plate D down close to the edge of the door, and as the door is opened the metal plate g forces the cam of the plate D upwards in the keeper o; thus causing the rod E to be drawn down, bringing down with it the plate F, which, catching under the lug x, in the cam G, draws said cam partially around, depressing the spring, and rings the bell by the point of the plate F sliding off of its lug.

Having thus fully described my invention, what I claim as new, and desire to secure by Letters Patent, is—

The plates C and g, cam D, rod E, plate F, cam G, spring K, clapper J, and bell H, all constructed, arranged, and operating in the manner described, whereby an alarm is given by the weather-strip, as set forth.

GEORGE W. CARPENTER.
